Bag Company, Minneapolis, Minn., a corporation of
Missouri

Filed Nov. 9, 1964, Ser. No. 409,800
2 Claims. (Cl. 229—66)

This invention relates to bags, and more particularly to an unravelable stitch type closure for bags.

In certain respects, this invention is an improvement upon a closure such as described in U.S. Patent 2,978,164 issued April 4, 1961, comprising a paper tape folded around an end of a bag and extending beyond the side edges of the bag, a line of single-thread stitching driven through the tape and through the walls of the bag and unravelable by pulling it from one end, and a tab adhered by adhesive to the tape over this one end of the thread and adapted to be grasped and pulled away from the tape to unravel the thread. Among the several objects of this invention may be noted the provision of closure of this general class, also having a tab adapted to be grasped and pulled away from the tape to unravel the thread, but in which the tab is held in place by being caught in the stitching; and the provision of such a closure in which, without adhesive, the stated end of the thread is sufficiently anchored to minimize the possibility of the thread unraveling it is desired to open the bag, without making it any more difficult deliberately to unravel the thread when it is desired to open the bag. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated.

FIG. 1 is a view in elevation of one end of a bag having a closure of this invention, showing the needle side of the closure;

FIG. 2 is a view showing the unraveling of the thread; and

FIG. 3 is an enlarged section taken on line 3—3 of FIG. 1.

Corresponding reference characters indicate corresponding parts throughout the several views of the drawings.

Referring to the drawings, a multiwall paper bag having an end closure of this invention is indicated at 1. For simplicity, the bag is shown as a two-ply bag, the inner ply being designated 3 and the outer ply 5. It will be understood that a multiwall bag usually will have more than two plies. As shown, the bag is a gusseted bag, the gussets being indicated at 7. The closure includes a paper tape 9 folded around the end of the bag. A line of stitching indicated at 11 is driven through the tape and through the walls of the bag securing together the walls adjacent the end of the bag. The length of the tape 9 is greater than the width of the bag, and the tape has end portions 13 and 15 which extend past the side edges of the bag. The stitching 11 extends completely throughout the length of the tape and, as shown, is driven through a narrow paper ribbon 17 constituting a so-called filler cord located on the side of the bag which is referred to as the needle side, this side being the side which faced the needle of the sewing machine employed for stitching. This filler cord extends throughout the length of the tape.

In accordance with this invention, the stitching at 11 is of a single thread readily unravelable chain stitch type. The single thread used for this stitching is desig-

2

nated 19. As will be understood by those conversant with the art, the stitching is formed by feeding the bag with the tape 9 folded around the end of the bag through a sewing machine having a needle which drives loops 21 (see FIG. 3) of the thread 19 through the bag, thereby forming needle holes 23 in the bag (see FIG. 2), the loops extending from the needle side of the tape 9 through the needle holes to the other side of the tape, each loop being laid over on the said other side and extending through the preceding loop 21. Reference may be made to United States Patent 2,978,164 for a detailed illustration of this type of stitching, which is unraveled with ease by taking hold of that end of the thread which is at the trailing end of the stitching in relation to the passage of the bag through the sewing machine, this being the end of the thread at that end of the stitching in the direction in which the loops are laid over (the right end of the stitching as illustrated in FIGS. 1 and 2 of the drawings herein). It will be understood that unraveling proceeds by successively pulling out the loops 21, the pulling out of each loop freeing the next loop so that it may be pulled out.

At 25 is indicated a pull tab, which may be made of paper, for example, lying between the filler cord 17 and the paper tape 9, the tab being held in place by the line of stitching 11. The tab 25 is located at the end of the stitching from which unraveling of the thread 19 progresses. By locating the tab on the needle side of the tape 9 beneath filler cord 17, the filler cord and thread 19 are removable with the tab as shown in FIG. 2. The length of the tab 25 is such that the tab extends inwardly from the end of the tape and filler cord and overlaps the adjacent gusset 7 of the bag 1. The tab 25 is substantially wider than the filler cord and, with the end stitch 27 cut as inherently results from the mode of manufacture of the bag, the outer end portion of the tab together with the end of the filler cord may be grasped and pulled to unravel the thread. By locating the tab between the filler cord and the tape, it is held in place solely by the stitching, without the use of adhesive. Despite the elimination of adhesive, it has been found that with the stitching driven through the filler cord, then the tab and then the tape 9, the end portion of the thread 19 between the right side edge of the bag (as viewed in FIG. 1) and the outer end of portion 15 of the tape is sufficiently anchored to minimize the possibility of the thread unraveling until it is desired to open the bag, without making it any more difficult deliberately to unravel the thread when it is desired to open the bag.

To open the bag, all that needs be done is to take hold of the right end of the filler cord 17 and the tab 25 between the thumb and forefinger, and pull them outwardly away from tape 9 of bag 1 as shown in FIG. 2. The tab comes away from the tape, carrying with it the filler cord 17 and thread 19, the thread unraveling as it is pulled out of the needle holes 23 in the tape 9.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A bag having at least one end closure constituted by a tape folded around the respective end of the bag, a filler cord on one side of the tape, a tab positioned between the tape and the filler cord and extending inwardly from one end of the tape, and a line of stitching driven

through the filler cord, the tab, the tape and the walls of the bag and extending throughout the length of the tape, the stitching being of a single thread readily unravelable chain stitch type which has loops extending from said one side of the tape through needle holes to the other side of the tape, each loop being laid over on said other side of the tape, said thread being readily unravelable by pulling it from said one end of the tape, the end of said filler cord and the tab at said one end of the tape being free for being grasped and pulled to separate the tab and filler cord from the bag and unravel the thread.

2. A bag having an end closure constituted by a paper tape folded around the respective end of the bag, the length of the tape being greater than the width of the bag and the tape having end portions extending past the side edges of the bag, a filler cord on one side of the tape and extending throughout the length of the tape, a tab positioned between the tape and the filler cord and extending from one end of the tape inwardly past the adjacent side edge of the bag, the tab being wider than the filler cord, and a line of stitching driven through the

15

20

filler cord, the tab, the tape and the walls of the bag and extending throughout the length of the tape and the filler cord, the stitching being of a single thread readily unravelable chain stitch type which has loops extending from one said side of the tape through needle holes to the other side of the tape, each loop being laid over on said other side of the tape, said thread being readily unravelable by pulling it from said one end of the tape, the stitch at said one end of the tape being cut so that the end of the filler cord and tab at said one end of the tape are free to be grasped and pulled to separate said tab and filler cord from the bag and unravel the thread.
